United States Patent Office.

A. E. BARNARD, OF AKRON, OHIO.

Letters Patent No. 71,567, dated December 3, 1867.

IMPROVED DIES FOR SWAGING AND FORMING BUNTER-SHAPES.

The Schedule referred to in these Letters Patent and making part of the same.

TO ALL WHOM IT MAY CONCERN:

Be it known that I, A. E. BARNARD, of Akron, in the county of Summit, and State of Ohio, have invented certain new and useful Improvements in Swages for Forging Car-Bunter Shapes; and I do hereby declare that the following is a full and complete description of the same, reference being had to the accompanying drawings, making a part of this specification, in which—

Figure 1 is a top view of a round-shouldered swage.

Figure 3 is a side view of fig. 1.

Figure 5 is an end view of the same.

Figure 2 is a view of a square-shouldered swage.

Figure 4 is a side view of fig. 2.

Figure 6 is an end view of the same.

Figure 7 is a view of a bunting-shape.

Figure 8 is a view of the two swages 1 2 together, with a bunting-iron between them.

Figure 9, a view of two swages, with a bunting-shape between them.

Like letters of reference refer to like parts in the several views.

The usual manner of forging bunter-shapes is by taking a piece of iron, of the proper length, width, and thickness, and lay across or upon a swage or former. Then, by repeated blows given by a hand-sledge, it is bent and beaten into the angles of the swage, the said angles being similar to those required for the shapes. By this manner of shaping the iron, one side only is formed at a time, the opposite side, which varies in shape, being given to the bunter afterwards, which is a matter of much trouble, for the reason that right angles A, fig. 7, are more or less destroyed by giving the proper curve, B, to the other side of the iron. Hence, the forging of bunter-irons or shapes in the usual manner is laborious and expensive, requiring much skill and length of time.

By the use of two swages, each one having the proper angle and curve for shaping the iron, and made to act one upon the other, with the bunting-iron C placed between them, as shown in fig. 8, and operated by a power-hammer, the labor and expense of forging them are very much lessened, and the time correspondingly shortened, producing an iron of greater precision, and hence a better article.

The shape of these dies or swages is shown in the drawings, of which fig. 1 is a top view of the swage for forming the curved side of the iron. B shows the curved section. An end view of the same is shown in fig. 5. Fig. 2 shows the lower swage for forming the angles, and of which A are angles. An end view of the same is shown in fig. 6. The two swages are shown as being together, with a bunting-shape between them. These male and female swages are also shown in fig. 9, in which figure the bunting-iron is shown as being placed on an inner angle of the swage, as at A' B', figs. 1 and 2.

What I claim as my improvement, and desire to secure by Letters Patent, is—

The herein-described swages for forging bunting-irons or shapes, when the same are operated by a tilting or power-hammer, in the manner substantially as set forth.
